Primary Examiner — T. Chase Nelson

(57) **CLAIM**

I claim the ornamental design for a contact lens case with cleaning compartment, as shown and described.

DESCRIPTION

FIG. 1 is a perspective view of the contact lens case with cleaning compartment, showing my design with the cleaning compartment cap removed for clarity of depiction.

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.
